FLOOR DRAIN

William M. Fraters, Balboa Island, Calif.

Application August 10, 1936, Serial No. 95,087

1 Claim. (Cl. 285—37)

This invention relates generally to the art of draining surfaces of all types and more particularly to draining floors, such as the floors of shower baths and the like. It is a primary object of this invention to provide an improved floor drain for conducting water from a shower bath floor or the like to a drain pipe. It is also an object of this invention to provide a floor drain of simple form and construction which is adapted to accommodate a flashing sheet of lead or other waterproof material for conducting away seepage from the floor. It is a further object of this invention to provide a floor drain adapted to conduct seepage water which may accumulate on the flashing sheet through the floor drain and into the drain pipe.

It is a further object of this invention to provide a floor drain which can be easily assembled and which can be readily adjusted for different thicknesses of floor. In this connection it is an object of the invention to provide a floor drain in which the parts thereof above the flashing sheet may be assembled in a unit and subsequently bolted as a unit to the main portion of the assembly.

It is a still further object of this invention to provide a floor drain having a drain supporting member adapted to screw on to the upper end of a drain pipe and which is adapted to support said drain pipe during installation of the device and before the drain floor has been laid.

It is a particular object of this invention to provide a floor drain having an annular clamping plate of improved design having a threaded hole in its center into which is adapted to be threaded a nipple carrying at its upper end and threaded thereon a drain inlet member. It is a particular object of the invention to provide a clamping plate which will effectively drain the accumulated seepage on it into the drain pipe.

It is a still further object to provide a floor drain which will not become clogged by careless laying of a cement floor around it.

These objects are achieved by the structure set forth in the drawing in which:

Fig. 1 is a sectional elevation of the invention; Fig. 2 is a plan on line 2—2 of Fig. 1, and

Fig. 3 is a sectional perspective view of the clamping plate of the invention.

Referring to the drawing it will be seen that the floor drain assembly has been shown as it would appear mounted in a floor. Reference numeral 11 indicates a wood support for the concrete floor 12 on which is laid a drain floor of tile 13. The floor drain itself comprises a basin

member generally indicated at 14 and shown as resting upon the wood support or timbers 11. The member 14 is adapted to support the entire assembly upon suitable supporting members 11 until the remainder of the floor portions 12 and 13 has been installed. The basin member 14 is shown as comprising an annular plate portion 15 and a downwardly extending hub 16. In the center of the plate portion 15 and a portion of the hub 16 is a recess 17 which terminates in shoulders 18 adjacent a threaded opening 19 at the lower terminus of the hub member 16. The basin member 14 also has an upwardly and outwardly extending peripheral flange 20 forming a shallow basin 21. Internally threaded holes 22 are also located in the member 14. A drain pipe 23 screws into the threaded opening 19 in the body member. A flashing sheet 24 of lead or other waterproof material rests upon the basin 21 of the member 14 and extends up and over the flange 20. This sheet has an annular opening 25 adapted to register with the recess 17 of the body member. Disposed on top of the flashing sheet 24 is a clamping plate 26 annular in shape which is internally threaded at 30. The clamping plate 26 has holes 27 into which are adapted to fit bolts 28 which screw into the threaded holes 22 of the body member 14. The flashing sheet 24 is punched or otherwise provided with openings 33 to accommodate the bolts 28. The clamping plate 26 also has downwardly and outwardly flared ports 29 adapted to drain any accumulation of seepage on top of the clamping plate member. These ports 29 are located above the recess 17 and will, therefore, permit drainage 35 thereinto.

The clamping plate 26 when clamped into position on top of the flashing sheet 24 assumes the basin like form of the upper portion 21 of the member 14, thus permitting seepage to accumulate on top of the plate 26 and drain through the ports 29.

A nipple 31 externally threaded at each end is adapted to thread into the internally threaded hole 30 in the clamping plate 26. However the threads in hole 30 terminate just short of the lower end of the opening in the hub portion 26'. This construction permits the nipple 31 to be threaded into the plate 26 but does not permit it to be threaded through it and protrude beyond it. At the upper end of this nipple 31 any suitable drain inlet member 32 may be threaded thereon. The invention contemplates the use of different length nipples in order to provide an 55

adjustment means to adapt the floor drain to different thicknesses of floors.

From the above description it is apparent that the flared construction of the drainage ports 29 provides adequate drainage of accumulated seepage water. This construction in connection with the large recess 17, and the fact that the clamping plate is so threaded as to prevent the nipple being threaded through it and protruding into the recess 17, prevents stoppage of the seepage drainage passages and the drain outlet itself by any possible influx of cement during the laying of the cement floor.

Furthermore, it will be seen that in assemblage of the device it is possible to assemble the upper portions as a unit, namely the inlet member 32, the nipple 31 and the clamping plate 26 and they may then be bolted down by the bolts 28 as a unit. This greatly facilitates installation of the device. This type of construction, embodying a clamping ring into which is threaded the

nipple carrying the drain inlet member, provides a much more rigid and solid floor drain than is possible with other types of construction.

I claim as my invention:

In a floor drain: a flat basin member having an upwardly extending flange at its periphery and a central drain opening; means for supporting the basin member in the floor; a water impervious sheet on the basin member; and a drain unit consisting of a flat clamping plate on said sheet having a central drain opening therethrough; a nipple threaded into said plate; a drain inlet member threaded to the upper end of the nipple; bolts extending through said plate outwardly of the drain opening therethrough and sheet into the basin member; said clamping plate having downwardly and outwardly flared drain holes opening into the central opening in the basin member.

WILLIAM M. FRATERS.
